MULTIPLE CABINET, SINK, AND MIRROR UNIT FOR BARBER SHOPS OR THE LIKE

Fred J. Piotraschke, Clayton, Mo.

Application August 20, 1956, Serial No. 42,655

Term of patent 3½ years

(Cl. D80—2)

The figure of the drawing is a perspective view showing my new design for a multiple cabinet, sink and mirror unit for barber shops or the like.

I claim:

The ornamental design for a multiple cabinet, sink and mirror unit for barber shops or the like, as shown.
